CRATE CORNER CONSTRUCTION

Edward M. Pennock, Minneapolis, Minn., assignor to G. H. Tennant Company, Minneapolis, Minn., a corporation of Minnesota

Application May 5, 1930. Serial No. 449,702

7 Claims. (Cl. 217—65)

My invention relates to milk bottle crates wherein the walls of the same are made of a series of slatted members which are superimposed. The slats ordinarily used in making crates of this nature are constructed so as to be connected at the corners and must be held so that they can expand and contract without breaking at the fastening means in the use of the crates.

10 A feature of the invention resides in means to reinforce the corners in such a manner so that when the crates are piled one upon the other, the load of the crates or the shock of dropping one crate onto the other will not break the securing means or crack the slats. This is accomplished by a suitable spacing means or shock absorber which carries the strain from top to bottom of the crate at the corners and thus relieves the strain on the rivets which hold 20 the corner members together and prevents breaking or cracking of the slats.

It is a feature of the invention to provide spacers between a pair of corner members which form the reinforcing inner and outer corner portions of the crate, the spacers being concealed between the corner members and adapted to take the load or shock coming against the upper surface of the crates. It is also a feature of my invention to provide suitable corner members 30 which may be made of any suitable material which are adapted to be shaped and spaced between inner and outer reinforcing corner plates which overlap the ends of the slats which make up the side walls of the crates.

35 Other details and important objects will be more fully and clearly set out in the specification and claims.

In the drawings forming a part of this specification:

40 Figure 1 is a perspective view of my milk bottle crate.

Figure 2 is an enlarged perspective detail of a form of the corner structure.

45 Figure 3 is another enlarged perspective detail of a form of the corner structure of my crate.

Figure 4 is a perspective view of an enlarged corner detail of my crate.

Figure 5 is a perspective detail of the corner of my crate, showing another form of the structure for reinforcing the same at the corners.

50 Figure 6 is a section on the line 6—6 of Figure 4.

Figure 7 is a section on the line 7—7 of Figure 5.

55 In the drawings my crate A is designed par-

ticularly for use for carrying milk bottles and is made up of a series of slats 10 which form the side walls. The slats 10 are held together by the inner right angular shaped corner member 11 which is provided with a stacking lug 12 on 60 the top end thereof and by means of the outer right angular corner member 13 which is formed with inwardly extending longitudinal flanges 14 which fit in the grooves 15 formed in the slats 10. The corner members 11 and 13 are held by 65 the rivets 16 which extend through the slats and are upset over the members 11 and 16 to lock the same rigidly in a manner to clamp the ends of the slats 10 of the crate. This provides a very strong reinforcing corner for the crate A 70 and holds the slats so that they are protected at the corners and yet are locked against longitudinal sliding owing to the flanges 14 and the slots 16 into which the flanges engage.

In connecting the corner members by the 75 rivets 16 the slats 10 are spaced apart in such a manner as to provide a slight space between each slat. This is done to permit the slats to expand and contract in the use of the crate A and is very important owing to the fact that 80 crates of this nature are usually subjected to considerable moisture at times and it is necessary that the crates are so made that the slats 10 will not be cracked at the point of riveting and thus cause the slats to easily break when 85 they are in use.

This form of fastening the slats together so that they are spaced apart does not make it necessary that each slat be riveted to the corner members 11 and 13. In fact, it is preferred to 90 construct the crate so that the top and bottom slats are riveted and then an intermediate slat is riveted, as illustrated in the drawings by the rivets 16. I have found that these crates are subjected to considerable hard usage and wear 95 and I have therefore provided a means of reinforcing my crates at the corners in such a manner as to distribute the load from some of the rivets and permit the same to be carried by virtually all of the rivets insofar as the stress or 100 strain is concerned, from the top edge to the bottom edge of the crate. One means of carrying out this reinforcing structure is illustrated in Figure 2 where I place a block 18 between the members 11 and 13 which is adapted to be 105 extended between the lower edge of the top slats 10 and the top edge of the intermediately riveted slats 10. Thus any weight upon the top of the crate A is carried through the block 18 to the intermediate slats which are riveted by the 110

rivets 16. This provides a structure where the strain can be distributed from the top edge to the intermediate slat so that the whole load or strain does not come wholly on the top rivets 16.

5 A further development of my reinforcing corner means for my crate A is illustrated in Figure 3 where I use a spacer block 18 between the top and intermediate slats 10 and a second spacer block 20 from the intermediate slat to the lower slat 10. These blocks 18 and 20 are concealed between the reinforcing plates 11 and 13 and it is only necessary to shorten the length of some of the slats 10 to permit the blocks to be easily inserted in place. These blocks are freely disposed and thus provide a very effective reinforcing means, and when the two blocks 18 and 19 are used the load on the upper top edge of the crate is carried from the top to the bottom slat being distributed through the intermediate

10 slat.

15 In Figure 4, I have illustrated a further development of my corner reinforcing means for crates A, and in this construction I provide a single member 22 which extends from the upper slats 10 to the lower slats 10. This member acts as a pillar to extend from the top to the bottom slats of the crate A and provides a reinforcing means which will carry the load placed on top of the crate from the top to the bottom or vice versa.

20 The idea of my reinforcing means at the corner may be further carried out as illustrated in Figure 5 to provide metal spacers 23 and 24 which are placed between the upper and the intermediate slat and between the intermediate and the lower slat of the crate. These metal reinforcing spacers may be of the form illustrated in Figure 7 and are concealed between the corner plates 11 and 13. It will be noted 25 that the ends of the slats 10 which abut the spacers are made sufficiently short so as to provide the space between the corner plates 11 and 13 to receive the spacers such as 18, 20, 22, 23 or 24. In Figure 6, I have illustrated a section 30 to show the relation of the spacer 22 as associated with the abutting ends of the slats 10 and showing the concealing of the spacer 22 between the sides 11 and 13.

35 It is important in my crate that the slats 10 which are not riveted to the corner plates 11 and 13 be held free to move sufficiently for expansion and contraction to provide a crate having side walls of a flexible or expandable nature so as to take care of the swelling and contracting 40 of the slats in the use of the crate. Thus by a structure as illustrated and described to reinforce the crate between the corner plates so that the load which may be placed upon the crate by many other crates placed one above the other 45 over the stacking corners 12, will not crush the lower crates or break the slats at the point of riveting particularly. I have found that this corner reinforcing means is highly important in the manufacture of crates to provide a crate 50 structure which will withstand the wear and tear under hard usage. The spacers protect the slats and assist in making a rigid corner structure which cannot be easily crushed by a top or bottom load in the use of the crates.

55 The particular construction of the outer corner plate 13 with the inturning flanges 14 which fit in the grooves 15 of each of the slats assists in carrying out the principles of my corner structure in holding the slats 10 in alinement and yet permitting the free movement of

the slats in relation to the connecting parts and transversely to the slats.

In accordance with the patent statutes I have described the features and particular construction of my crate and while I desire to illustrate and set forth the best embodiment and uses thereof, I desire to have it understood that the same is only suggestive of a means of carrying out the principles of the invention and that the same may be varied within the scope of the following claims and still maintain the primary features of the invention.

I claim:

1. A crate structure including corner plates adapted to cover the inside and outside of the crate corners, a series of spaced slats adapted to be secured between said corner plates, some of said slats being riveted and some of said slats being free to move transversely of each other between said plates, means for holding said plates in longitudinal alinement, and means not materially affected vertically by expansion on account of moisture for reinforcing the corners of said crate between said plates to carry the load from top to bottom of said crate.

2. A crate structure applicable to a slatted walled crate, inner and outer plate corner members, means in said corner members for holding all of the slats of the walls in alinement, rivet means for holding some of said slats rigidly between said corner plates, and spacer means not materially affected vertically by expansion on account of moisture between some of said slats concealed between said corner plates to distribute the load from one slat to another in the corners.

3. A corner construction for a slatted walled crate including, inner and outer corner plates, longitudinal inturned flanges on one of said plates, transverse slits in the slats of the walls of said crate adapted to be engaged by said longitudinal flanges, rivet means for holding some of the slats rigidly between said corner plates, and wooden block-like spacer means having vertically extending grain between the riveted slats with the ends of the unriveted slats abutting said spacer means between said plates.

4. A milk bottle crate including, walls made of a series of spaced superimposed edge to edge slats, corner reinforcing plates extending over said slats, rivet means for connecting said corner reinforcing means to said slats, and extending through some of said slats, the slats intermediate the riveted slats being free to slide up and down, and metal spacer load carrying members between the riveted slats concealed in the corners of said crate and adapted to distribute the load from one riveted slat to another riveted slat.

5. A milk bottle crate including, side walls made of a series of spaced superimposed edge to edge slats, metal plate-like virtually right angular corner reinforcing members adapted to extend along the inside and the outside of the corners of said crate to collectively hold the ends of the slats together, means in said corner plates for holding the slats in longitudinal alinement, means for rigidly securing some of said slats to said corner plates with the other of said slats spaced from the rigidly secured slats to allow for expansion and contraction thereof, and longitudinally extending column load carrying spacer means having a low longitudinal coefficient of expansion due to moisture between said plates adapted to distribute the load throughout the corner portions of said crate.

6. A milk bottle crate comprising slatted wooden walls, metal reinforcing plates extending along the inside and the outside of the corners of said crate, and longitudinally extending spacer
5 means having a low longitudinal coefficient of expansion due to moisture within said corners adapted to provide column reinforcing to distribute the load from the top to the bottom of the crate, and means for holding some of the 10 slats of the walls freely spaced from others of the slats of the walls.

7. A corner structure for a crate in combina-

tion with slatted wooden side walls, inner and outer metal reinforcing plates covering and supporting the ends of the slatted walls, column spacer means not materially affected vertically by expansion due to water adapted to distribute the load from one slat to the other of the walls of the crate, and means for holding some of the slats of the walls abutting with said column supporting means and freely disposed in relation to fixed slats held by said corner plates.
